CASE FOR SKI EQUIPMENT

Michael P. Alexander, Westland, Lorenzo V. Alexander, Detroit, John Birka, Dearborn, and Darryl D. Flesher, Dearborn Heights, Mich., assignors to Cavall Specialties, Inc., Warren, Mich., a corporation of Michigan

Filed June 7, 1967, Ser. No. 7,407

Term of patent 14 years

(Cl. D87—2)

FIG. 1

FIG. 4

FIG. 2

FIG. 3

We claim:

The ornamental design for a case for ski equipment, as shown.
